UNITED STATES PATENT OFFICE.

CHARLES F. BLOCH, OF CALIFORNIA, MISSOURI.

PENCIL-SHARPENER.

1,080,411.

Specification of Letters Patent.

Patented Dec. 2, 1913.

Application filed June 15, 1910. Serial No. 567,008.

To all whom it may concern:

Be it known that I, CHARLES F. BLOCH, a citizen of the United States, residing at California, in the county of Moniteau and State 5 of Missouri, have invented new and useful Improvements in Pencil- Sharpeners, of which the following is a specification.

This invention relates to pencil sharpeners of that type including a hollow conical 10 rotary cutter into which the pencil is inserted to be sharpened by the blade of the cutter.

The invention has for one of its objects to improve and simplify pencil sharpeners of this type so as to be reliable and efficient in 15 use, and in which the blade is spirally arranged so as to produce a drawing cut on the pencil and thus prevent the lead from breaking, as usually occurs from the scraping action of a straight blade.

Another object of the invention is to provide a combined receptacle and support for 20 receiving the shavings and for holding the cutter.

With these objects in view and others, as 25 will appear as the description proceeds, the invention comprises the various novel features of construction and arrangement of parts which will be more fully described hereinafter and set forth with particularity 30 in the claim appended hereto.

In the accompanying drawing, which illustrates one embodiment of the invention, Figure 1 is a perspective view of the device. Fig. 2 is a central transverse section 35 thereof. Fig. 3 is a cross sectional view of the cutter.

Similar reference characters are employed 40 to designate corresponding parts throughout the views.

Referring to the drawing, A designates a combined receptacle and support which forms the base of the device. This receptacle is in the form of a cup and consists of a bottom 1 and an upstanding marginal flange 45

2 that forms side and end walls, the cup being open at the top. Rising from the side walls are upwardly-extending arms 3 which support the rotary cutter B. This cutter consists of a hollow conical body 4 disposed 50 horizontally between the arms 3. One end of the cutter body is open to receive the end of the pencil to be sharpened, and at this open end, the body 4 is externally reduced to

provide a journal 5 that extends into a journal bearing 6 in one of the arms 3, and at 55 this journal is formed a shoulder 6 which engages the said arm 3 to prevent longitudinal movement of the cutter. The members 3 are spaced apart a distance less than the length of the cutter B, so that the latter can 60 not have axial movement after it is positioned, and consequently the journal 5 is maintained in the bearing 6 without any special fastening means. The opposite end of the cutter is formed with an enlarged 65 head 7 which has its transverse end face bearing against the inner surface of the opposite arm 3, and in this latter arm is an opening 8 through which passes a journal 9 that has a crank 10 whereby the cutter can 70 be turned. The cutter has a spiral groove 11 through which the shavings pass and at one side of this groove is a knife 12 fastened in any suitable manner. This knife is of spiral form and the cutting edge thereof ex- 75 tends into the hollow of the cutter body so as to shave down the pencil to a sharp point. By means of the spiral cutting edge of the knife, a drawing cut is produced so that the tendency to breakage of the lead is reduced 80 to a minimum. The shavings drop out of the slot of the cutter into the receptacle or cut under the same and are there collected.

From the foregoing description, taken in connection with the accompanying drawing, 85 the advantages of the construction and of the method of operation will be readily apparent to those skilled in the art to which the invention appertains, and while I have described the principle of operation of the 90 invention, together with the device which I now consider to be the best embodiment thereof, I desire to have it understood that the device shown is merely illustrative, and that such changes may be made when de- 95 sired as are within the scope of the claim appended hereto.

Having thus described the invention, what I claim as new, is:—

A device of the class described comprising 100 a receptacle, a pair of parallel arms being formed on the said receptacle and projecting upwardly therefrom, the said arms being provided adjacent their upper ends with alining openings, a rotary cutter disposed 105 between said arms and having one of its

ends reduced for the reception of the opening within the adjacent arm, the pencil opening in the cutter extending inwardly from the said end thereof, and an operating crank 5 having its engaging shaft extremity rotatably mounted within the opening in the opposite arm and projecting inwardly therefrom, the cutter being provided with a re-

cess in the adjacent end receiving the said crank end.

In testimony whereof I affix my signature in presence of two witnesses.

CHARLES F. BLOCH.
